UNITED STATES PATENT OFFICE.

FREDERIC JOHN WHINCAP, OF GRAND RAPIDS, MICHIGAN, ASSIGNOR TO KIRSCH COMPANY, OF STURGIS, MICHIGAN, A CORPORATION OF MICHIGAN.

DESIGN FOR A SUPPORTING BRACKET FOR CURTAIN POLES.

Application filed December 17, 1928. Serial No. 29,311. Term of patent 3½ years.

To all whom it may concern:

Be it known that I, FREDERIC JOHN WHINCAP, a subject of the King of England, and a resident of Grand Rapids, county of Kent, and State of Michigan, have invented a new, original, and ornamental Design for a Supporting Bracket for Curtain Poles, of which the following is a specification, refer-

ence being had to the accompanying drawing, forming a part hereof, which is a front perspective view of the supporting bracket for curtain poles, showing my new design.

I claim:

The ornamental design for a supporting bracket for curtain poles as shown.

FREDERIC JOHN WHINCAP.
